No. 793,553.

Patented June 27, 1905.

UNITED STATES PATENT OFFICE.

FRANS VAN THIEL, OF HELMOND, NETHERLANDS.

SCREW-NUT SECURER.

SPECIFICATION forming part of Letters Patent No. 793,553, dated June 27, 1905.

Application filed December 27, 1904. Serial No. 238,446.

To all whom it may concern:

Be it known that I, FRANS VAN THIEL, a subject of the Queen of the Netherlands, and a resident at Helmond, Veesstraat, Netherlands, 5 have invented certain new and useful Improvements in Screw-Nut Securers, of which the following is a full, clear, and exact description.

The object of the invention in question is a nut-securer which offers advantages, owing 0 to its simple construction.

Figure 1 of the drawings represents a top view of the securer for nuts placed at a short distance from each other; Fig. 2, a side view of the same; Fig. 3, a top view of another 5 form of the securer for nuts having a greater space between them; Fig. 4, a side view of the same, and Fig. 5 the nut-securer applied to a fish-joint of a rail.

The nut-securer consists of a plate *a*, on 0 which the catch in the form of a resilient steel bar *b* or the like is fastened in a piece *f*, joined to the same, *a*. This steel bar *b* presses with its free end against shoulders *c* of the

screw-nut *d*, thus securing it. To liberate a nut held fast in this manner, a pin *s* in the 25 plate under the steel bar *b* is turned by means of a key or the like and the bar *b* is raised.

What I claim as my invention, and desire to secure by Letters Patent, is—

A nut-lock consisting of an ordinary screw-bolt and a nut having projecting teeth at the base of the side surfaces, of a plate *a* perforated to register with the holes in the fish-plate and rail ends, of a spring *b* having one end secured to said plate *a* and the other end adapted to engage the teeth of the nut, and of a revoluble pin *s*, turning in holes of plate *a*, said pin having a flat part to allow of the spring 30 engaging the teeth, and having a round part to hold said spring out of engagement with the teeth, substantially as described.

In testimony whereof I affix my signature.

FRANS VAN THIEL.

In presence of—

AIRE H. VOORWINDEN,
OSKAR KÜNZELL.
